[57] CLAIM

The ornamental design for an extension lever attachment for a motor vehicle door handle, substantially as shown.

DESCRIPTION

FIG. 1 is a perspective view of an extension lever attachment for a motor vehicle door handle showing my new design;

FIG. 2 is a top plan view;

FIG. 3 is a front elevational view;

FIG. 4 is a rear elevational view;

FIG. 5 is a side elevational view;

FIG. 6 is an opposite side elevational view; and

FIG. 7 is a bottom plan view thereof.

FIG. 1

FIG. 2

FIG. 3

FIG. 4

FIG. 5

FIG. 6
